Gess & Beegman

UNITED STATES PATENT OFFICE.

PHILIP DRESSLER, OF ZANESVILLE, OHIO, ASSIGNOR TO AMERICAN DRESSLER TUNNEL KILNS, INC., OF NEW YORK, N. Y., A CORPORATION OF NEW YORK.

TUNNEL KILN.

Application filed January 22, 1919. Serial No. 272,420.

To all whom it may concern:

Be it known that I, PHILIP DRESSLER, a subject of the Kingdom of Great Britain, residing at Zanesville, in the county of 5 Muskingum, State of Ohio, have invented certain new and useful Improvements in Tunnel Kilns, of which the following is a specification.

My improvement relates to tunnel kilns of 10 the muffle type as generally described in U. S. Letters Patent granted to C. Dressler, No. 1,170,428 dated Feb. 1, 1916. In the type of kiln disclosed in said patent, the gas is introduced into the combustion chambers 15 at the temperature of the atmosphere, or slightly above the temperature of the atmosphere, while the air used in combustion with the gas is introduced directly from the goods chamber at a high temperature. To obtain 20 the best results, it is desirable that both the gas and air should be heated to a high temperature before they are introduced into the combustion chambers.

The object of my invention, therefore, is a 25 construction by means of which both gas and air may be pre-heated before being introduced into the combustion chambers, and distributed as desired at different portions of the chambers.

30 The accompanying drawings will serve to illustrate my invention, in which:

Fig. 1 is a horizontal section and partial plan, illustrating a construction in which both the gas and air are heated external to 35 the combustion chambers before being introduced into the combustion chambers.

Fig. 2 is a vertical section taken substantially on the line II—II of Fig. 1.

Fig. 3 is a horizontal section and partial 40 plan illustrating a modification of the construction shown in Fig. 1.

Fig. 4 is a vertical section taken substantially on the line IV—IV of Fig. 3.

Fig. 5 is a horizontal section and partial 45 plan showing a modification of the construction shown in Fig. 3.

Fig. 6 is a horizontal section and partial plan showing a further modification of the construction shown in Fig. 3.

50 In the drawings, 5 indicates a kiln structure. 6, combustion chambers arranged on each side of the interior of the structure. In construction, the combustion chambers are substantially the same as described in the

prior patent of Dressler, to which reference 55 has above been made. Arranged on one side of the kiln, is a gas heating chamber 7, and on the opposite side, an air heating chamber 8. Arranged in these chambers are a series 60 of flues 9, the construction of the chambers being substantially the same. Gas is fed to the gas heating chamber through a pipe 10 and air to the air heating chamber through a pipe 11. Heated gas is conveyed from the gas heating chamber 7 to the combustion 65 chambers 6, through a pipe 12, and the air from the air heating chamber to the combustion chambers 6 through a pipe 13. The space surrounding the flues 9 in gas heating chamber 7, is connected to one of the 70 combustion chambers 6 through a pipe 14, and the similar space in air heating chamber 8 to one of the combustion chambers 6 through a pipe 15. The spaces in the heating chambers 7 and 8 surrounding the flues 75 9, are connected to chimney flues 16.

The operation of the construction so far as described is as follows: Gas entering through the pipe 10 and air through the pipe 11, pass through the flues 9 and respectively through the pipes 12 and 13 into the combustion chambers 6. The outgoing products of combustion from the combustion chambers pass through pipes 14 and 15 to the space surrounding the flues 9, thereby 85 heating the gas and air, and pass out through the chimney flues 16.

Referring now to Fig. 3. In this figure, the combustion chambers are divided into two sections, 6, at the right of the figure, 90 which corresponds to that shown in Fig. 1, and 6^a at the left of the figure. The combustion chambers 6^a are provided with extensions 6^b, which extensions are exposed to the temperature of the interior of the 95 kiln, and are therefore heated. The extensions 6^b are carried through the walls of the kiln and are open as shown at 6^c. The air used in combustion in the combustion chambers 6^a, enters through the opening 6^c, is heated in passing through the extension 6^b, and is brought in contact, in the combustion chambers, with the heated gas derived from the gas heating chamber 7. The arrangement of parts, so far as the chambers 100 6 are concerned, at the right of the figure, is the same as in Fig. 1.

Referring now to Fig. 5. The construc-

tion shown in this figure is the same as in Fig. 3, with the exception that the combustion chambers 6 at the right hand side of the figure are not provided with the tubular extensions 6^a, as shown in Figs. 1 and 2. The tubular extensions 6^a are shown in Figs. 1 and 2 as connected to a pipe 17, by means of which the products of combustion passing through the extensions 6^a may be carried 10 through gas heating chamber 7 and thence to the chimney flues 16, as shown in Fig. 6. It will be noted that in Figs. 1, 3 and 6, the combustion chambers 6 are provided with exit pipes 14 and 15, and their extensions 15 6^a with exit pipe 17 through both of which the products of combustion may be conveyed to the gas and air heating chambers 7 and 8, and thence to the chimney flues 16, the purpose of this arrangement being to provide 20 that only a portion of the products of combustion shall pass through the extensions 6^a and thereby insure that the temperature at the right hand end of the kiln, i. e., the exit end, shall be lower than over that portion 25 of the kiln occupied by the chambers 6.

In Fig. 6, the gas fed to the chambers 6^a is heated by the products of combustion derived from the extensions 6^a of the chambers 6, which pass through pipe 17, chamber 7 30 and chimney flue 16. Gas heated by passage through pipes 9 of chamber 7, passes through pipe 12^a to the forward end of the chambers 6^a where it mingles with heated air which passes from the interior of the furnace 35 through the open end 18 of the chambers 6^a. The temperature of the products of combustion so derived, is necessarily lower than that derived from the chambers 6 and 6^a, and the purpose of this arrangement is to provide 40 that the temperature at the entrance end of the kiln, i. e., the left hand end, shall be lower than the temperature at the center of the kiln. It will be observed from this figure, that the gas and the air fed to the chambers 6 are heated by the outgoing products 45 of combustion from chambers 6^a passing through pipes 14^a and 15^a, and also from chambers 6 passing through pipes 14 and

15, which insures the highest temperature in the chambers 6.

I wish it understood that the various constructions shown in the different figures, are merely illustrative of such as may be used to pre-heat gas and air and to distribute pre-heated gas and air at different temperatures 55 to different sections along the length of the kiln, and that various changes may be made without in any wise departing from the intent of my invention.

Having thus described my invention, I 60 claim:

1. In a tunnel kiln the combination of heating means therefor comprising internal combustion chambers, means for supplying fluid material to said chambers to maintain 65 combustion therein and means comprising a plurality of outlets from said combustion chambers for regulably preheating said material by products of combustion withdrawn from said chambers.

2. In a tunnel kiln the combination of heating means therefor comprising internal combustion chambers having outlets through which products of combustion may be withdrawn from said chambers at different temperatures and means for supplying gaseous material to said combustion chambers to maintain combustion therein including provisions external to the kiln for regulably preheating said material by products of 75 combustion withdrawn from the combustion chambers through said outlets.

3. In a tunnel kiln and in combination with combustion chambers located on each side of the interior of the kiln, means for pre-heating the gas and air used in such combustion chambers, said means consisting of chambers through which the gas and air are fed and heated, the gas by the waste products of combustion from the body of a combustion chamber, and the air from an extension of the combustion chamber.

In testimony whereof, I affix my signature.

PHILIP DRESSLER.
